US00D958276S

(12) **United States Design Patent** (10) **Patent No.:** **US D958,276 S**
Woodward et al. (45) **Date of Patent:** **** Jul. 19, 2022**

(54) **GOLF CLUB HEAD**

(71) Applicant: **KARSTEN MANUFACTURING CORPORATION**, Phoenix, AZ (US)

(72) Inventors: **Alexander G. Woodward**, Phoenix, AZ (US); **Xiaojian Chen**, Phoenix, AZ (US)

(73) Assignee: **Karsten Manufacturing Coperation**, Phoenix, AZ (US)

(**) Term: **15 Years**

(21) Appl. No.: **29/751,844**

(22) Filed: **Sep. 23, 2020**

(51) **LOC (13) Cl.** **21-02**

(52) **U.S. Cl.**

USPC **D21/752**

(57) **CLAIM**

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a top view of the golf club head of FIG. 1;

FIG. 4 is a bottom view of the golf club head of FIG. 1;

FIG. 5 is a front view of the golf club head of FIG. 1;

FIG. 6 is a rear view of the golf club head of FIG. 1;

FIG. 7 is a heel side view of the golf club head of FIG. 1; and,

FIG. 8 is a toe side view of the golf club head of FIG. 1. The broken lines shown on the drawings form no part of the claimed design.

1 Claim, 5 Drawing Sheets
